DESIGN FOR A COMBINATION STAMP HOLDER, PAD AND INK RESERVOIR UNIT

Stanley R. Hershman, Los Angeles, Calif.

Application November 3, 1944, Serial No. 116,125

Term of patent 7 years

(Cl. D64—10)

To all whom it may concern:

Be it known that I, Stanley R. Hershman, a citizen of the United States of America, residing in the city of Los Angeles, in the county of Los Angeles, State of California, have invented a new, original, and ornamental Design for a Combination Stamp Holder, Pad and Ink Reservoir Unit, of which the following is a specification, reference being had to the accompanying drawing, forming a part thereof.

Fig. 1 is a perspective view of a combination

stamp holder, pad and ink reservoir unit showing my new design;

Fig. 2 is a top plan view of the same;

Fig. 3 is a front elevational view of said device;

Fig. 4 is an end elevational view, and

Fig. 5 is a vertical central cross-sectional view.

I claim:

The ornamental design for a combination stamp holder, pad and ink reservoir unit, substantially as shown.

STANLEY R. HERSHMAN.
